UNITED STATES PATENT OFFICE

JAMES R. BILLUPS, OF SHREVEPORT, LOUISIANA, ASSIGNOR OF ONE-HALF TO WILLIAM B. McCORMICK, OF SHREVEPORT, LOUISIANA

RAILROAD TIE AND FASTENER FOR USE THEREWITH

Application filed February 6, 1929. Serial No. 337,923.

This invention relates to railroad ties and fasteners for use in connection therewith, the primary object being to provide a concrete tie so constructed as to be free to flex under 5 the weight of rolling stock travelling thereover.

Another object is to provide a concrete tie so constructed as to prevent creeping of the tie either transversely or longitudinally 10 after being properly positioned on the roadbed.

A further object is to provide a concrete tie which will not tilt transversely and affords the maximum supporting area for the track 15 rails, thereby reducing materially the number of ties required in the track construction.

A still further object is to provide novel means for fastening rails to the tie, said means being simple and efficient and adapted 20 for use under different conditions and situations.

With the foregoing and other objects in view which will appear as the description proceeds, the invention resides in the combination and arrangement of parts and in the details of construction hereinafter described 25 and claimed, it being understood that changes in the precise embodiment of the invention herein disclosed may be made within the scope 30 of what is claimed without departing from the spirit of the invention.

In the accompanying drawings the preferred forms of the invention have been shown.

35 In said drawings,

Figure 1 is a top plan view of a concrete tie constructed in accordance with the present invention and having rails fastened thereto, a portion of one of the rails being broken away.

Figure 2 is a side elevation of the structure illustrated in Figure 1, the rails being shown in section.

45 Figure 3 is a section on line 3—3, Figure 2.

Figure 4 is a section on line 4—4, Figure 1.

Figure 5 is an end elevation of the tie, a portion of a rail being shown thereon.

Figure 6 is a plan view, on a reduced scale, 50 of a modified form of concrete tie.

Figure 7 is a perspective view of one form of rail fastener for use with the tie.

Figure 8 is a perspective view of another form of fastening plate especially adapted for use when making repairs. 55

Figure 9 is a perspective view of another tie plate for use in fastening rails to a tie at switches.

Referring to the figures by characters of reference, 1 and 2 designate two oppositely 60 disposed tie sections formed of concrete. Each section is preferably beveled at its sides as indicated at 3 and provided with oppositely extending arms 4 so located as to constitute supports for track rails R when said 65 rails are placed proper distances apart.

During the formation of the sections 1 and 2 of the tie, one or more flexible metal members, preferably of steel cable, are embedded in the sections and extend longitudinally 70 thereof. These reinforcing cables or the like have been indicated at 5 and while two of them have been shown embedded in the concrete sections of the tie, it is to be understood 75 that one or more of the members can be used. As shown in Figure 3 the ends of the cables are untwisted and the strands 6 are extended into the arms 4 and longitudinally and transversely within the end portions of the sections 1 and 2 so that the cables are thus 80 secured anchored in the tie.

The primary purpose of the cable or cables 5 is to provide a flexible connection between the sections 1 and 2. Said cables can be made of a metal that will not corrode or, if preferred, that portion of the cable bridging the space between the sections 1 and 2 can be housed in a casing 7 of lead or other suitable protecting material that will not interfere with the desired flexing of the cable at this 90 point.

By referring particularly to Figures 2 and 4 it will be noted that the upper portions of the tie sections abut at their inner ends as long as the sections are in alinement. A 95 transverse recess 8 is formed between the lower portions of the sections and it is through this recess that the flexible connecting elements extend. By providing recess 8 it becomes possible for the outer ends of the 100

tie sections to sag under the weight of a load, the two sections thus moving relative to each other.

While the ties are generally constructed with straight arms 4 as shown in Figure 1, it may be found advantageous, along curved stretches of track, to use ties having curved arms 9 as shown in Figure 6, these arms following the curvature of the rails. It might be added that in all forms of tie, any suitable reinforcing means 10 of coarse mesh metal fabric or of metal rods can be embedded in each section of the tie.

Formed in the bottom surface of the tie beneath those points where the rails R are to be supported are recesses 11 and in each recess is seated a plate 12 adapted to receive the lower end portions of bolts 13. Recesses 14 are formed in the upper surface of the tie at those points where the rails are to be supported and each of these recesses is adapted to receive a tie plate 15 having rail engaging flanges 16 extending toward each other. Oppositely extending ears 17 are formed integral with the tie plate and are positioned where they can be engaged by the bolts 13 the upper ends of which carry nuts 18 that bear upon the ears. The outer flange 16 of each plate has an integral rail brace 19.

Ties such as herein described are adapted to be used in lieu of the ordinary wooden ties. Because of the arms 4 fewer ties of this improved form can be used in a given length of track than are required where the usual wooden ties are employed. When the ties are properly set in the road-bed the arms 4 will prevent them from creeping longitudinally and these arms have the further function of holding the ties against lateral tilting. When the original installation is being made, tie plates such as shown in Figures 1, 2, and 4 and in detail in Figure 7 are fastened to the ties and the rails are inserted longitudinally into engagement with the flanges of these plates. The attachment of the plates to the ties can be made either before or after said plates have been assembled with the rails. After the parts have thus been fastened together, the rails will of course be held at the proper distances apart and it becomes unnecessary to use special rail fastening means such as commonly employed.

When it is found necessary to make repairs by removing one of the tie plates and substituting another, said plate after being cut or broken away from the rail engaged thereby and detached from the tie, can be replaced by a tie plate 20 such as illustrated in Figure 8. This plate has only one rail engaging flange 21 and one ear 22. It has ribs 23 for engaging one base flange of the rail R and an aperture 24 for the reception of one of the bolts. This tie plate is adapted to be slipped into position between the tie and the rail so that the base flanges will rest thereon

between flange 21 and ribs 23. The usual bolts 13 can be employed for fastening the plate to the tie but the nut 18 can directly engage one of the base flanges of the rail or a suitable rail engaging clip, as will be obvious.

Where rails diverge, as at a switch, a tie plate of the type illustrated in Figure 9 can be used. This plate 25 has rail engaging flanges 26 and oppositely extending ears 27. The flanges diverge so as properly to engage the diverging rails and a tapered block 28 can be formed on the plate between the flanges for fitting snugly between the webs of the diverging rails.

By constructing a tie as herein described the same can flex readily about the point of connection between the sections thereof whenever the end portions of the tie are subjected to a load. Thus a tie having many of the resilient characteristics of a wooden tie is produced without the use of wood or any similar substances likely to deteriorate from the action of moisture and wear.

What is claimed is:

1. A railroad tie including separate reinforced concrete sections, a metallic cable embedded in the sections and extending longitudinally thereof, said cable constituting the sole connection between the sections. 90
2. A railroad tie including separate concrete sections each having oppositely extending arms constituting rail supports, said sections being positioned end to end, and a cable embedded in and extending longitudinally of the sections, said cable constituting the sole connection between the sections and said sections being adapted to swing relative to each other about their point of connection. 95
3. A railroad tie including reinforced concrete sections arranged end to end, each section having oppositely extending rail supporting arms, a cable embedded in said sections and constituting the sole connection therebetween, said sections being adapted to swing relative to each other about the point of connection, the ends of the cable being untwisted to provide strands extending into the arms and into the ends of the sections. 105
4. A railroad tie including reinforced concrete sections arranged end to end, a twisted cable embedded in said sections and constituting the sole connection therebetween, said sections being adapted to swing relative to each other about the point of connection, the ends of the cable being untwisted to provide strands extending into the ends of the sections to anchor the cable. 115
5. A railroad tie including reinforced concrete sections arranged end to end, a twisted cable embedded in said sections and constituting the sole connection therebetween, said sections being adapted to swing relative to each other about the point of connection, the ends of the cable being untwisted to provide strands extending into the ends of the sec- 125

tions to anchor the cable, and a tubular metal protecting sheathing extending into the sections and bridging the space therebetween, said sheathing housing that portion of the

5 cable between the sections.

In testimony that I claim the foregoing as my own, I have hereto affixed my signature.

JAMES R. BILLUPS.
